UNITED STATES PATENT OFFICE

MILTON VINCENT BROWN, OF GUTHRIE, OKLAHOMA, ASSIGNOR OF ONE-HALF TO PAUL RICHARD BARNES, OF GUTHRIE, OKLAHOMA

SIGN

Application filed April 27, 1929. Serial No. 358,625.

This invention relates to new and improved advertising signs embodying luminous gases as the medium of illumination.

Another object of the invention contemplates the provision and arrangement of containers for the luminous substance forming a background and face for the stenciled placards.

A further object of the invention consists of a frame for the containers to support same in such positions that the stencils may spell or otherwise exhibit the advertising matter to advantage and in such a way that same may be easily read.

More specifically stated the containers and stencils or placards therefor are shrouded by frame structures to individually set forth each of the letters or legends whereby the sign will appear equally as attractive and magnetic in the daylight.

With the above and other objects in view, the invention further consists of the following novel features and details of construction, to be hereinafter more fully described, illustrated in the accompanying drawings and pointed out in the appended claims.

In the drawings:

Figure 1 is an elevation of my improved form of sign.

Figure 2 is a longitudinal sectional view taken therethrough.

Figure 3 is a view similar to Figure 2 taken midway therethrough to illustrate the relative arrangement of the containers in top plan.

Figure 4 is a vertical sectional view taken on line 4—4 of Figure 1.

Figure 5 is an enlarged and fragmentary detail sectional view through the means of support for the containers.

Figure 6 is a fragmentary elevation of a modified form of sign partly broken away to illustrate the construction thereof.

Figure 7 is a longitudinal sectional view taken through the modification.

Referring to the drawings in detail wherein like characters of reference denote corresponding parts, the reference character 10 indicates generally a frame of elongated formation having a sill 11 seated upon the upper rail therefor and curved upon its upper sur-

face to accommodate a roof or shield portion 12 having sufficient projection upon the side edges and ends thereof to shed water from the opposed sides of the frame and appurtenances thereto.

Plate members 13, having rightangularly disposed offset extremities 14, are vertically disposed at spaced intervals within the frame and having connection with the inner sides of the opposed side rails. Angle brackets 15, carried adjacent the lowermost ends of the plate members 13, support the bulk or weight of the display apparatus set forth in the following description.

The display apparatus, referred to, primarily resides in the construction and provision of hollow blocks or containers, generally designated as at 16 and which are of relatively flat formation. The blocks are preferably formed of glass or other transparent material and formed with pockets 17 to contain neon or other luminous rarefied gases and sealed therein after the manner of vacuum tubes and the like. If desired, the orifices or pockets having communication with the pockets may be in the nature of sleeves 18 primarily intended for insertion and projection of the positive and negative terminals of a secondary low voltage circuit. The plates 16 are arranged in the manner suggested in Figure 2 of the drawings in spaced relation and seated adjacent the lowermost corner portions therefor upon the immediate angle bracket 15.

Nailers or other forms of insulators, indicated as at 18' and arranged in the manner shown in Figures 1, 2 and 4 of the drawings, carry the positive and negative lead wires 19 and 20 with the secondary binding post of a transformer, not shown. Conducting wires 21, carried by and projecting from the lead wires 19 and 20, are passed through the bores of the sleeves 18 as shown in Figures 2 and 4 of the drawings to energize or ionize the gas to produce a light of a characteristic orange-pink in color.

Flange members 22, carried by and having the side edges therefor laterally disposed within the frame upon fastening elements 23 embedded terminally thereof within the plate

members 13, carry spacing sleeves 24 to define channel pockets 25 between the side portions of the plate members 13 and the flanges 22. The side portions of each of the plates 16 are receivable within the pockets 25 in the manner shown in Figure 5 of the drawings. Stencils or other forms of placards indicated as at 26 face the opposed sides of the hollow blocks 16 to exhibit the luminous color caused by the ionized gas therein through the portions removed in the stencils and through sight openings in the cover plates 27 arranged upon the opposite sides of the frame. The cover plates are primarily designed to completely obscure from view the frame structure, insulators and lead wires therefor and the marginal edges of the plates or blocks 16.

Frame members 28, carried upon the outer surfaces of the side plates 27, exhibit the stenciled indicia or legends through openings 29 and provide borders about the exhibited advertising matter whereby the latter may be exhibited to advantage both day and night.

By removing the frames 28 and loosening the side flanges 22 sufficiently, the stencils 26 may be changed or otherwise substituted to exhibit any form or spell any words desired.

In the form of my invention disclosed in Figures 6 and 7 of the drawings, a box-like housing 30 of relatively flat formation is disclosed and which is cut, stenciled or otherwise treated to outline letters, numerals or other legends in the opposed side walls thereof. Elongated channel members 31, arranged in pairs and in spaced parallelism vertically within the housing 30, accommodate blocks or plate members 32 corresponding in shape and construction to those illustrated, as at 16 in Figures 1 to 5 inclusive. Slots or spaces 33, vertically disposed adjacent and within the uppermost ends of the channel members 31, permit reception of conducting wire sleeves 34 therein when the hollow blocks or containers 32 are lowered in position. To facilitate such insertion, it is first incumbent upon the operator to raise lids, doors or other closures, such as indicated at 35, and hinged as at 36, upon the upper portion of the housing. The closures will also permit wiring of the blocks or containers 32 subsequent to disposition within the housing.

By reason of the fact that the housings 30 may be arranged in assembled units, same will permit and facilitate changing of the reading or wording of the sign to such an extent that several different forms of advertising may be exhibited at intervals throughout the day, for instance, show places, such as theaters, amusement parks and the like may advertise, through illustrations, future shows or performances.

The invention is susceptible of various changes in its form, proportions and minor details of construction, and the right is here-

in reserved to make such changes as properly fall within the scope of the appended claims.

Having thus described the invention, what is claimed is:—

1. An illuminating device of the character described comprising a housing having openings in the opposed side walls thereof, channel members vertically disposed at spaced intervals within said housing and openings, containers of hollow block like formation receivable within the guideways formed by the channel members, stenciled placards facing said containers, and said containers being filled with an electrically luminous gas designed to exhibit light of even density over the entire surfaces thereof exposed through the portions removed in the housing and the stenciled portions in the placards.

2. An illuminating device of the character described comprising a housing having openings in the opposed side walls thereof, channel members vertically disposed at spaced intervals within said housing and openings, containers of hollow block like formation receivable within the guideways formed by the channel members, said containers being filled with an electrically luminous gas designed to exhibit light of even density over the entire surfaces thereof exposed through the portions removed in the housing, and stencil members removably secured within the channel members and on the exposed sides of the containers.

In testimony whereof I affix my signature.

MILTON VINCENT BROWN.
